W. A. HEIDE

SPARK PLUG

Filed Jan. 29, 1923

Patented June 16, 1925.

UNITED STATES PATENT OFFICE.

WILLIAM A. HEIDE, OF DETROIT, MICHIGAN.

SPARK PLUG.

Application filed January 29, 1923. Serial No. 615,727.

To all whom it may concern:

Be it known that I, WILLIAM A. HEIDE, a citizen of the United States, residing at Detroit, in the county of Wayne and State 5 of Michigan, have invented a new and useful Spark Plug, of which the following is a specification.

This invention relates to spark plugs, one of its objects being to provide a device 10 of this character the parts of which can be assembled and taken apart readily, said spark plug including a central electrode the terminal of which can be adjusted angularly relative to a fixed electrode, thus to 15 vary the size of the spark gap.

Another object is to provide a novel arrangement of insulating means.

A still further object is to provide a central electrode which can be adjusted longitudinally relative to the casing or shell of 20 the spark plug.

With the foregoing and other objects in view which will appear as the description proceeds, the invention consists of certain 25 novel details of construction and combinations of parts which will be hereinafter more fully described and pointed out in the claims.

In the accompanying drawing, which is 30 a central longitudinal section through a spark plug, the preferred form of the invention has been shown.

Referring to the drawing by characters of reference 1 designates the shell of the 35 spark plug having the usual tapered threaded end portion 2 and the opening extending longitudinally through this shell is slightly tapered inwardly from both ends toward the center of the shell as shown at 3.

Extending into the shell from opposite 40 ends thereof are oppositely arranged tapered plugs 4 and 5 preferably though not necessarily formed of insulating material. The inner or small ends of these plugs can, if desired, be spaced apart as shown at 6 so as to receive a gasket 6' of compressible material between them. A sheet or sheets 7 of mica or the like can be extended around the plugs so that when the plugs are forced 50 toward each other they will bind the mica against the wall of the opening in the shell 1 and thus hold it in place securely.

A tubular tie bolt 8 is extended longitudinally through the plugs and is provided 55 at one end with a head 9 while its other end is screw threaded as at 10. Head 9 is

adapted to engage the large end of plug 5 while the threaded end 10 is adapted to be engaged by a nut 11 bearing against the large end of the plug 4. By tightening the 60 nut the plugs will be forced toward each other and will become properly centered in the shell 1 so as to clamp the layer of insulating material against the wall of the opening 3.

Extending longitudinally through the tie bolt 8 is a tubular core 12 having its end portions screw threaded as shown at 13 and 14, and provided with a head 12', by which the tubular core 12 can be rotated readily. 70

The threads 13 engage one end of the tie bolt 8 while the threads 14 extend beyond the other end of the tie bolt and do not engage it. One or more longitudinal grooves 15 can be provided in the outer surface of 75 the core 12 and extend from the threads 13 toward the other end of the core, intersecting the threads 14. The outer end of the core is adapted to support an adjusting nut 16 engaging the threaded end portions 17 of an electrode 18. This electrode extends through and is adapted to be rotated within the core 12 and has a collar 19 adapted to be drawn against one end of the core 13. A terminal 20 extends from the collar 19 and is offset laterally and adapted to cooperate with a fixed terminal 21 preferably located between the cylinder bore B and the intake port P of the engine to which the spark plug is attached. A lock nut 22 also engages a threaded end 17 of the electrode and a binding nut 23 is adapted to engage said end 17 and cooperate with the nut 22 to secure the terminal of a wire to the electrode as shown at 24.

It will be understood that by loosening the nuts 16, 22 and 23 the electrode 18 can be rotated so as to bring its terminal 20 to any desired position relative to the electrode 21, thus to vary the size of the spark gap. 100 By then tightening nut 16 the collar 19 will be drawn tightly against core 12 so as to hold the electrode against accidental rotation. Obviously by rotating the core 12 within the tie bolt 8 the electrode 18 can be shifted longitudinally toward or from the electrode 21, there being a nut 25 engaging the threaded portion 14 of the core and bearing on the end of the tie bolt 8 so as to act as a lock nut to hold the core against accidental rotation. 105

As before pointed out the nut 11 consti-

tutes a means for adjusting the plugs 4 and 5 toward each other, thereby to clamp the insulating sheet 7 against the shell 1 and hold the parts properly assembled.

5 It will be noted that this spark plug constitutes an efficient seal to prevent leakage of gas. Furthermore by having the groove or grooves 15 any heated air or moisture is free to escape readily from the center of the 10 plug. The outer end of electrode 18 is flattened at 26 so that the electrode can be rotated readily to shift the terminal 20 relative to the electrode 21.

What is claimed is:

15 1. A spark plug including a shell, opposed tapered plugs therein, a tubular tie bolt extending through the plugs and constituting means for adjusting the plugs toward each other, a tubular core adjustable longitudinally within the tie bolt and having a longitudinal groove extending to one end thereof, an electrode mounted for rotation within the core, a collar on the electrode bearing against the core, an offset terminal 20 on the electrode, and means engaging the electrode and core for holding the electrode against movement relative to the core.

20 2. A spark plug including a shell, opposed tapered plugs within and insulated from the shell, a tubular tie bolt extending through the plugs for holding them wedged within the shell, a tubular core extending longitudinally through the bolts, an electrode extending through and rotatable within the

core, said electrode having an offset terminal, means upon the electrode and cooperating with the core for holding the electrode against rotation, said core being adjustable longitudinally to shift the electrode in the direction of its length. 35

40 3. The combination with an engine structure having an intake port and a cylinder bore, and a fixed terminal between the intake and the cylinder bore, of a spark plug including a shell, opposed tapered plugs 45 therein and insulated therefrom, a tubular tie bolt extending through the plug for holding them wedged within the shell, a tubular core extending longitudinally through the tie bolt, an electrode extending longitudinally through the core and having an offset terminal, said electrode being rotatable within the core to swing the terminal relative to the fixed terminal, means upon the electrode and cooperating with the core for holding said electrode against rotation, said core being adjustable longitudinally within the tie bolt to shift the electrode bodily toward or from the fixed terminal, and means for holding the tie bolt against adjustment. 50

55 In testimony that I claim the foregoing as my own, I have hereto affixed my signature in the presence of two witnesses.

WILLIAM A. HEIDE.
